(57) **CLAIM**

The ornamental design for a combined stabilizer pad and handle apparatus, as shown and described.

DESCRIPTION

FIG. 1 is a perspective view of the combined stabilizer pad and handle apparatus showing a first embodiment of the design;

FIG. 2 is a top view of the first embodiment of the design; FIG. 3 is a front elevation view of the first embodiment of the design;

FIG. 4 is a side elevation view of the first embodiment of the design, the opposite side elevation would be a mirror image; FIG. 5 is a perspective view of a second embodiment of the design;

FIG. 6 is a top view of the second embodiment of the design; and

FIG. 7 is a front side elevation view of the second embodiment of the design; and,

FIG. 8 is a side elevation view of the second embodiment of the design the opposite side elevation would be a mirror image.

The broken lines defining the stabilizer arm and stabilizer platform are shown for illustrative purposes and do not form a part of the claimed design.
